UNITED STATES PATENT OFFICE.

FREDERICK BENNETT, OF RAVENSWOOD, NEW YORK, ASSIGNOR TO WALKER & BENNETT MANUFACTURING COMPANY, OF NEW YORK, N. Y., A CORPORATION OF NEW YORK.

CAR-SEAT.

1,291,732.

Specification of Letters Patent. Patented Jan. 21, 1919.

Application filed November 18, 1912, Serial No. 732,094. Renewed June 26, 1918. Serial No. 242,093.

To all whom it may concern:

Be it known that I, FREDERICK BENNETT, a citizen of the United States, residing at Ravenswood, in the county of Queens and 5 State of New York, have invented certain new and useful Improvements in Car-Seats, of which the following is a specification.

This invention relates to car-seats of the walk-over reversible-back type.

10 The object of the invention is to so mount the back on the back standards, that the back will begin to move with a positive movement upon the initial movement of the standards, instead of there being a movement first of 15 the standards and then a final reversing movement of the back, as in known constructions. This makes possible, the reversing of the back, without manual force exerted for other purposes than for shifting the back 20 from one side to the other.

A further object of the invention is to so construct the shifting mechanism, that the strain upon the parts will be mainly in the direction of their lengths, rather than breaking or torsional transverse strains.

Other objects of the invention which have to do with durability, simplicity and ease of operation, will become apparent in the description.

30 Referring to the drawings—

Figure 1 is a transverse vertical section of a car seat constructed in accordance with my invention;

Fig. 2 is a detail section taken about on 35 line α — α of Fig. 1;

Fig. 3 is a perspective view of one of the lock plates.

Fig. 4 is a vertical section showing the back of my car seat in middle position in the 40 course of being shifted, with the front plate removed therefrom;

Fig. 5 is a section taken along the line 5—5 of Fig. 4; and

Fig. 6 is a cross section taken along the 45 line 6—6 of Fig. 4.

It will be understood that the parts shown, with the exception of the pedestal, are duplicated on each side of the seat.

Referring to the drawings, the numeral 1 50 designates the pedestal having the usual arms 2, to which are attached by suitable clips, the tie-rods 3. Rigidly supported adjacent to the pedestals, where two pedestals are employed, are plates 4. In case where only one

pedestal is employed, it will be understood 55 that one plate will be rigidly supported adjacent to the aisle pedestal and the other may be securely attached to the side of the car.

Each plate is provided with a pocket 5 formed by a flanged off-set plate 5'. The 60 numeral 6 indicates one of the back-standards which are preferably hollow, being composed of two flanged sections secured together in any suitable manner. Each standard is provided with a short stud or 65 pin 7, suitably journaled in the plates 4 and upon these studs or pivots the back standards are adapted to rock back and forth in shifting the seat and back.

The numeral 8 indicates one of the operating levers. These levers are preferably inclosed within the hollow side arms and are provided near the lower end with a stud or pin 10 operative in closed vertical slots 11 made in the pocket plates 5'. Each operating lever is also provided with a short stud or pin 12 operative in the horizontal curved slot 13 in the pocket plate and each of said levers is provided with a closed slot 14 in which a pin 14' carried by each side 75 standard is adapted to operate. The operating levers project upwardly to a point near the upper ends of the back standards and carry at their upper ends studs 15 which work in curved slots 16 in the upper ends of 80 the standards. Pivoted to the back-standard 6 as indicated at 17, are brackets 18 to which the back is rigidly secured, thus when the back is attached to the bracket, it is capable of a rotary or reversing movement upon the 90 back-standard. The standards are extended below their pivots 7 and have their lower ends connected by a rod 19 which works in the recesses 20 in lock-plates 21, which lock-plates are, as shown best in Fig. 2, open at 95 their bottoms and are provided with stops 21', the purpose of which will presently become apparent. These plates are rigidly supported on the tie-rods 3, being provided with engaging ends 22', which embrace said 100 tie-rods, so that any oscillating tendency on the part of the lock-plates will be prevented and a rigid construction produced.

The numeral 23 designates the foot-rest which comprises a cross-bar 24 and two side 105 arms 25. The foot rest is pivoted upon bolts 22 mounted on the lower portions of the lock plates 21, and each arm of the

rest is provided with an elongated slot 26, at its upper end, through which the connecting rod 19 extends. The numeral 27 designates one of the rockers, upon which the seat is carried. These rockers, of which there are two, are provided with downwardly extending ears 28, having vertical slots 29 therein, for the passage of the rod 19, whereby a loose pivotal connection is established 10 between the back-standards, rockers and foot-rest, and whereby the foot-rest and seat are shifted together.

In operation, force is applied to the top of the back, which will obviously have a 15 tendency to both shift the back and rotate it or reverse it upon the back-standards. The reversing movement of the back from the position it occupies as shown in the drawings, will cause the operating levers to be 20 drawn downwardly and during the movement of the whole back, both in shifting and reversing, will cause the pins or studs 10, 12, 14 and 15 to move to the opposite ends of their respective slots, so that by the time 25 the whole seat is shifted and reversed, all of the pins, with the exception of the pins 10 and 14, will occupy the opposite ends of their respective slots. During this movement, the back-standards, swinging upon their pivots, 30 will swing the rod 19 from beneath one of the stops 21' and cause it to travel through the recesses 20 in the lock-plates 21, and through the pivotal connections between the rockers, back-standards and foot-rest, the 35 rockers and foot-rest will be shifted to a position opposite that they now occupy, bringing the rod 19 under the opposite stop 21' in which position the seat will be shifted, and the back reversed from the position 40 shown. By reason of the slightly down-turned position of the stops 21', it will be impossible to operate the parts by any pressure applied accidentally to the foot-rest as it will be noted that any pressure applied to 45 the bottom of the foot-rest will simply bring the rod 19 with greater force against the stops 21', it being apparent that the only way to shift and reverse the back, is to rock it upon its pivot 7, the movement of the rod 50 19 being concentric with the pivot 7.

Having thus fully described my invention, what I claim is:

1. A car seat, having in combination a side plate, a back-standard rockably pivoted 55 with relation to said side plate, an operating lever carried by the back-standard and slideable longitudinally with relation thereto, means for bringing about the relative longitudinal movement between the operating lever and the back-standard by the movement 60 of the back-standard, consisting of a

stud in said operating lever and a curved slot in said side plate, and an operative connection between the operating lever and the seat-back whereby the seat-back is reversed 65 in passing from one extreme position to the other.

2. A car seat, having in combination a side plate, a back-standard rockably pivoted with relation to the side plate, an operating 70 lever carried by the back-standard and movable longitudinally and also rockably with relation thereto, a locking plate provided with oppositely disposed locking recesses, and a protruding rod carried by the back- 75 standard and adapted to detachably engage either recess to hold said back-standard in its moved position.

3. A car seat, having in combination, a side plate, having an open pocket, a hollow 80 back-standard rockably pivoted to the side plate and movable in said pocket, an operating lever inclosed within said back-standard and slideable longitudinally with relation thereto, a curved slot carried by the 85 side plate co-acting with a stud carried by the operating lever, whereby the operating lever is longitudinally moved with relation to the back-standard during the movement of said back-standard, and an operative connection between the operating lever and the seat back, whereby the seat back is reversed in passing from one extreme position to the other, a locking plate provided with oppositely disposed locking recesses, and means 90 carried by the back-standard and adapted to detachably engage either recess to hold said back-standard in its moved position.

4. A car seat, having in combination, a side plate, a back-standard rockably pivoted 1 with relation to said side-plate, an operating lever carried by the back standard and movable longitudinally and rockably with relation thereto, means for positively bringing about the longitudinal and rockable movement of the operating lever by the movement of the back-standard consisting of a stud in said operating lever and a curved slot in said side plate, and a sliding pivotal engagement between the lower end of the operating lever and said side plate, and an operative connection between the upper end of the operating lever and the seat back, whereby said seat back is reversed in passing from one extreme position to the other.

In testimony whereof I affix my signature in the presence of two witnesses.

FREDERICK BENNETT.
